UNITED STATES PATENT OFFICE

JACOB E. BRUBAKER, OF LANCASTER, PENNSYLVANIA, ASSIGNOR TO THE HUBLEY MANUFACTURING CO., OF LANCASTER, PENNSYLVANIA, A CORPORATION OF PENNSYLVANIA

TOY DETONATOR

Application filed October 23, 1931. Serial No. 570,721.

This invention relates to toys and more particularly to a toy detonator adapted for the explosion of caps or similar explosive devices.

5 One of the objects of the invention is to provide a device so constructed as to increase the intensity of the report of the explosion, while at the same time rendering the effects of the explosion entirely safe. That is to say, the invention contemplates the provision of a hollow shell or casing having an anvil provided with a central opening communicating with the detonating chamber of the shell and an anvil formed at a downward 15 angle around said opening so that when the cap explodes the elements of explosion will be directed toward the ground.

Another object of the invention is to provide a novel detonating shell which is susceptible of embodiment in various forms and configurations and has a hammer element detachably interlocked therewith in such a way that it can be disconnected by proper manipulation, but under ordinary circumstances will 25 not separate from the shell, thereby facilitating handling, and at the same time materially enhancing the value of the invention from a practical and manufacturing standpoint since it permits of properly connecting the shell and anvil without the necessity of springs or other devices which necessarily complicate devices of this kind.

30 A further object of the invention is to provide a device wherein the hammer is substantially entirely concealed within the hollow shell or casing so that only the string to which the hammer is attached issues from the end of the shell opposite the hammer.

With the above and other objects in view, 35 which will more readily appear as the nature of the invention is better understood, the same consists in the novel construction and arrangement of parts hereinafter more fully described, illustrated and claimed.

40 Preferred and practical embodiments of the invention are shown in the accompanying drawings, in which:—

Figure 1 is an elevation of the present improved toy.

45 Figure 2 is a vertical sectional view.

Figure 3 is a bottom plan view partly broken away to show the anvil portion of the shell.

Figure 4 is a horizontal cross sectional view taken on the line 4—4 of Figure 4. 55

Figure 5 is an elevation of a modification of the invention.

Figure 6 is a vertical cross sectional view of the construction shown in Figure 5.

Similar reference characters designate corresponding parts throughout the several figures of the drawings. 60

The present invention includes in its organization a hollow shell or casing designed generally as A and which may assume various shapes and forms so far as design is concerned and may be susceptible of a wide range of exterior ornamentation. In each instance, however, the shell A essentially comprises a hollow body having the wall or walls 1 enclosing a detonating chamber 2 provided at its upper end with an opening 3. This opening serves as an outlet or guide for a manipulating string S connected with a hammer device B which cooperates with the inclined anvil face 4 at the end of the shell opposite the opening 3. The anvil face 4 is preferably inclined downwardly and outwardly or, in other words, is of substantially frustoconical shape and communicates with the detonating chamber 2 through the opening 5 so that the exploded cap or cartridge will be discharged toward the ground or floor. 65

70 The hammer B preferably includes a head portion 6 and a shank 7 connected by an inclined anvil surface 8. This face cooperates with the anvil surface 4 on the detonating shell to initially receive and hold therebetween a cap or other explosive element due

75 to the weight of the shell 1, and subsequently explode the same when the entire device including the shell A or hammer B are dropped to the ground or other surface by manipulating the string S. The inner end or tail portion of the hammer B is provided with the offset or outwardly extending fins 9 and 10, the former being, in the example shown, of substantially V-shaped cross section and the latter having the offset wings or equivalent elements 11 (Figure 4) so that the fin 10 80

85

90

95

100

will be wider than the fin 9. The purpose of this construction is to detachably lock or key the hammer B and shell A together. That is to say, the opening 5 in the body of the shell A is provided with a recess 9a which is of the same shape as the fin 9 on the tail of the hammer shank 7. When it is desired to assemble the shell and the hammer, the latter is placed at such an angle that the 10 enlarged fin portion 10 may fit in the opening 5 and when the fin 9 having the same shape as the recess 9a registers therewith, the shank of the hammer may be inserted into the chamber 2. A slight twist of the hammer 15 or shell circumferentially will, of course, throw the fin 9 out of register with the slot 9a so that the parts will be held against accidental separation.

Another feature of the hammer B resides 20 in offsetting the end of the hammer shank 7 as indicated at 12 to accommodate the string S. That is, the end of the shank is perforated and offset so that the end of the string S may be threaded through the perforation or eye 25 and knotted at the end, and the body of the string will fit into the groove 13 made possible by the offsetting, thereby to center the string axially with reference to the hammer.

In use the shell A is held in the hand and 30 since the hammer B is loosely held interlocked with the shell, a cap C may be readily placed between the anvil faces 4 and 8. By supporting the device with the string or cord S the weight of the shell A will, of course, be imposed on the hammer B and thus hold 35 the cap between the anvil surfaces. Upon permitting the entire device to drop while held by the string S, the force of the hollow body or shell A moving toward the anvil B 40 when the latter strikes the ground or other surface will cause the cap to be exploded and, therefore, make a loud report. The intensity of the report is increased because of the hollow detonating chamber 2 and also since 45 the force of the explosion is directed downwardly the sound waves resulting from the explosion will strike the ground which acts as a sounding board to cause the said sound waves to more effectively rebound to further increase the intensity of the report.

Without further description it is thought 50 that the features and advantages of the invention will be readily apparent to those skilled in the art, and it will of course be understood that changes in the form, proportion and minor details of construction may be resorted to, without departing from the spirit of the invention and scope of the appended claims.

I claim:

1. A toy detonator including a body having a detonating chamber and provided with diametrically disposed large and small openings, an anvil on the body surrounding the large opening, a hammer including a head

cooperating with the said anvil and also having a shank extending into said chamber, means on the body and on the inner end of the shank for detachably interlocking the hammer in the body, a flexible support for 70 the detonator passing through the said small opening and connected to the end of the hammer shank.

2. A toy detonator including a body having a detonating chamber and provided with 75 diametrically disposed large and small openings, an anvil formed on the body and surrounding the said large opening thereof, said anvil having a notch located at the edge of the opening, a hammer including a head cooperating with the said anvil and also having a shank extending into the said chamber, laterally extending wings formed on the inner end of the shank, one of said wings fitting 80 the shape of the notch for passage therethrough and the other of which is larger whereby the shank of the hammer may be fitted into and through the larger opening into the detonating chamber and may be turned out of registry with the notch to loosely 85 interlock the hammer with the body, and a flexible support for the detonator passing through said small opening and connected to the end of the hammer shank.

3. A toy detonator including a body having a detonating chamber provided with an opening, an anvil formed adjacent said opening, and a hammer adapted to cooperate with said anvil, said hammer including an enlarged head portion and an enlarged tail 100 portion connected by a relatively narrow intermediate shank, and means formed on the body adjacent the opening and on the tail of the shank whereby the hammer and body may be loosely interlocked.

4. A toy detonator including a hollow body having a detonating chamber provided with a relatively constricted opening, an anvil formed adjacent said opening, a hammer including a head for cooperating with said anvil to explode a cap held between the hammer head and the anvil, a shank extending from the head of the hammer and adapted to loosely fit into the constricted opening of the body and to enter said detonating chamber, and means on the body and on the inner end of the shank for detachably interlocking the hammer and body.

5. A toy detonator including a hollow body 120 providing a detonating chamber having an opening, an anvil formed at the location of said opening, a supporting cord outlet formed opposite said opening, a hammer including a head portion adapted to cooperate 125 with the anvil, and having a shank passing through said opening and into the detonating chamber, means on the body and on the inner end of the hammer to loosely interlock the hammer and the body, and means also on 130

the inner end of the shank for centering and securing an attaching cord to the hammer.

6. A toy detonator including a body having a detonating chamber and provided with a large opening and a small opening oppositely disposed, an anvil on the body surrounding the large opening, a hammer including a head cooperating with the said anvil and also having a shank portion terminating within the detonating chamber, a flexible member connected with the end of said shank portion concealed within the detonating chamber and passing through said small opening, and means for preventing the separation of the hammer from the body.

7. A toy detonator including a body having a detonating chamber and provided with a large opening and a small opening oppositely disposed, an anvil on the body surrounding the large opening, a hammer including a head cooperating with the said anvil, a flexible member connected with the hammer, and means for preventing separation of the hammer from the body.

25 In testimony whereof I hereunto affix my signature.

JACOB E. BRUBAKER.
